UNITED STATES PATENT OFFICE.

RALPH F. SCHNEIDER, OF NEW YORK, N. Y., ASSIGNEE TO CHARLES J. TAGLIABUE, OF BROOKLYN, NEW YORK.

MANOMETER.

1,134,352.

Specification of Letters Patent.

Patented Apr. 6, 1915.

Application filed June 27, 1912. Serial No. 706,145.

To all whom it may concern:

Be it known that I, RALPH F. SCHNEIDER, a citizen of the United States, and a resident of the borough of Brooklyn, county of Kings, city and State of New York, have invented certain new and useful Improvements in Manometers, of which the following is a specification.

My invention relates to manometers and more particularly to mercurial manometers and has for its object to provide an instrument of this kind which, when not in use, may readily be folded into a relatively small compass and easily unfolded or extended to an operative condition for use and in which the mercury is securely sealed against spilling in the inoperative condition of the instrument.

My improvement will be fully described hereinafter and the features of novelty will be pointed out in the appended claims.

Reference is to be had to the accompanying drawings in which—

Figure 1 is an elevation of one form of my invention illustrated in position for use; Fig. 2 is a similar view showing the instrument in its folded or inoperative condition; Figs. 3 and 4 are detail views in section; Figs. 5, 6, 7 and 8 are views similar to Figs. 1, 2, 3 and 4 of another form of my improvement.

Referring more particularly to Figs. 1 to 4 inclusive, the instrument is constructed with preferably transparent main tubes 10 and 11 preferably arranged parallel to each other, the tube 11 forming a receptacle which is connected at one end by means of a transverse tube 12 with the tube 11 to form a substantially U-shaped tube adapted to contain mercury or other indicating medium 13 and comprising what might be termed a main section. The opposite open ends of said tube 10 and receptacle 11 extend into caps 14 and 15 and are secured therein in any suitable manner, said caps being provided with bores 16 and 17 which extend transversely to the axes of the tubes 10 and 11. The said bores 16 and 17 are preferably tapered in opposite directions and are arranged in axial alignment as shown best in Figs. 3 and 4. Passages or channels 18 and 19 extend from said bores 16 and 17 toward the tubes 10 and 11 and communicate therewith for the purpose to be more clearly brought out hereinafter. A plug 20 is

formed with preferably tapered bearing portions 21 rotatably mounted in the bores 16 and 17 of said caps 14 and 15, said plug being held against displacement in the direction of its axis by means of nuts 22 screwed upon suitable screw-threaded portions of said plug and preferably seated in depressions 23 formed in the caps as clearly shown in Figs. 3 and 4. The said plug 20 is further provided with a nozzle or coupling member 24 by means of which the instrument may be connected in any customary manner with the source of pressure or other force to be measured. A third auxiliary tube 25 has its one end secured in a depression 26 formed in said plug 20 in any suitable manner and either has its opposite end entirely open or covered as shown in Fig. 1 of the drawings, an air vent 26 being provided in this last named instance and comprises what might be termed an auxiliary section. A passage or channel 27 extends axially of the plug 20 and communicates at one end with a passage 28, the free end of which is arranged in line with the channel 18 and connects at its other end with another channel 29 which in turn communicates with the tube 25. Another passage 30 in said plug extends inwardly from the free end of the nozzle 24 and connects with a short passage 31 which extends at an angle thereto and has its free end arranged in line with the channel 19, the two channels 27 and 30 having no direct communication with each other as can be seen by referring to Figs. 3 and 4 of the drawings.

In the inoperative or folded condition of the instrument the auxiliary tube 25 extends between the main tubes 10 and 11 as shown best in Fig. 2. In this condition of the parts the channels 28 and 31 project in a direction away from the channels 18 and 19, which latter channels are thus covered and sealed by the outer surface of the portions 21 of the plug 20. The mouth of each channel 28 and 31 is in turn closed by the surface of the bores 16 and 17, it being understood that the tapered portions 21 fit said bores 16 and 17 with what might be termed a running fit or, in other words, sufficiently snug to seal the channels 18 and 19 as described and yet permit a rotation of said portions 21 in said bores 16 and 17. The relative positions of the various channels with the parts in the condition so far described are clearly illus-

trated in Fig. 4. When it is desired to use the instrument the auxiliary tube 25 is swung to the position illustrated in Fig. 1 and the plug 20 consequently rotated relatively to the caps 14 and 15. This operation brings the mouth of the channel 28 into registry with the channel 18 and the mouth of the channel 31 into registry with the channel 19 and thus connects the tube 11 with the nozzle 24 and the auxiliary tube 10 with the main tube 25 which auxiliary tube thus substantially forms an extension of said main tube as clearly shown in Fig. 3. If the nozzle 24 is now connected with the source of pressure or other force to be measured the effects of this pressure or other force will be transmitted through the channels 30, 31 and 19 and to the tube 11, and will be exerted on the upper surface of the mercury or other indicating medium 13 in the tube 11. This upper surface of said indicating medium will be depressed by this force and will accordingly cause the mercury or other indicating medium to rise in the tube 10, and if the force is great enough, the said indicating medium will be forced through the channels 18, 28, 27 and 29 and into the tube 25. In order that a reading may be had in a simple manner, this tube 25 is provided with a scale 32 suitably divided and indicating in a desired manner the pressure exerted.

In order to provide for an accurate reading of a pressure which is not great enough to force the mercury or other indicating medium completely through the channels 18, 28, 27 and 29, and to compensate for these channels in which the mercury would ordinarily not be visible, a portion of the scale is produced on the tube 11 as indicated at 33. In the illustration this portion 33 of the scale reads from zero to forty, while the portion 32 or in other words a continuation of the scale on the tube 25 reads from forty upward. Thus if the pressure exerted on the mercury should be less than that indicated by the point 40 on the scale 33 the reading would be taken from this portion 33 by noting at what point thereon the upper end of the mercury column or other indicating medium in the tube 11 was located. If the pressure should be sufficient to depress the mercury in the tube 11 sufficiently to cause its upper end to register with the point 40 in the scale 33, then it will be found that the upper end of the mercury column which is normally in the tube 10 is also in registry with the point 40 on the scale 32 of the tube 25. Any increased pressure would now be readable on the scale 32 so that it will be seen that an accurate reading of all pressures from zero upward may be readily had with my improved instrument even though a part thereof is made of opaque material. In this form of my instrument the tube 25 is thus swiveled in the sleeves 14 and 15, the

bores 16 and 17 of which form bearings for the preferably tapered portions 21 of the plug 20 to permit said tube 25 to be swung to an operative position in which as before stated it is virtually a continuation or an extension of the tube 10. When the instrument is in its folded condition as shown in Fig. 2 no part thereof projects beyond the open ends of the tubes 10 and 11 or rather beyond the sleeves 14 and 15 carried thereby so that the one usual long and fragile leg of the tube which has heretofore been necessary in order to secure the required length of tube to properly accommodate the maximum rise of the mercury necessary to measure the maximum pressures for which the instrument is designed is done away with and the danger of breakage is practically obviated. In addition to this a manometer made according to my invention also occupies a minimum amount of space when not in use and is therefore easily carried and readily shipped. By constructing the tube 25 in the manner so far described and illustrated in Figs. 1, 2, 3 and 4, the portions 21 form trunnions extending in opposite directions so that by journaling these trunnions in bearings as illustrated the upper ends of the tubes 10 and 11 are securely braced and form a rigid structure which is not easily fractured or injured.

In the form of my invention illustrated in Figs. 5, 6, 7 and 8 the instrument comprises main tubes 10^a and 11^a the latter of which forms a receptacle connected at 12^a with the tube 10^a to form a substantially U-shaped tube also comprising what might be termed a main section and also adapted to contain mercury 13^a or other indicating medium in the same manner as in the first form of my improvement. The open end of the main tube or receptacle 11^a extends into a cap 15^a and is secured therein in any suitable manner, said cap 15^a being provided with a preferably tapered transverse bore 17^a and a channel 19^a extending from said bore and communicating with the tube 11^a. The said cap 15^a is further provided with a nozzle or other coupling member 24^a, having a channel 30^a extending from the said bore 17^a to the free end of the nozzle and preferably in alignment with the channel 19^a, the said nozzle affording a means through the medium of which the instrument may be connected in any customary manner with the source of pressure or other force to be measured. A tapered plug 34 is rotatably mounted in the bore 17^a and is maintained against movement in an axial direction by means of a screw and nut 22^a, a handle 34^a being provided for manipulating the plug 34. A passage 34^b extends through the plug 34 in line with the channels 19^a and 30^a and is arranged to bring these two channels into communication with each other or to dis-

connect them according to the position of the plug as will be more fully set forth hereinafter. The open end of the main tube 10^a is secured in any suitable manner in a cap 14^a in the same manner as in Fig. 1, said cap 14^a being also provided with a transverse preferably tapered bore 16^a and a channel 18^a extending therefrom and communicating with the tube 10^a. An elbow or plug 20^a has a tapered portion 21^a rotatably mounted in said bore 16^a and is also secured therein against any movement relatively to the cap 14^a other than a rotative one by means of a screw and nut 22^a. A channel 27^a similar to the channel 27 is formed in said elbow and communicates at one end with a channel 28^a similar to the channel 28 and in line with the channel 18^a. The opposite end of the channel 27^a is in communication with an auxiliary tube 25^a similar to the tube 25 and also forming what might be termed an auxiliary section, said tube 25^a having its one end secured in the cap 14^a in any suitable manner and its other end either entirely open or substantially closed as illustrated and provided with an air vent 26^a in the same way as in Fig. 1. A portion of a scale 32^a and a continuing scale portion 33^a may be produced respectively on the tubes 25^a and 11^a and correspond in function and operation to the scale portions 32 and 33 of the first form of my improvement.

In the form of my invention illustrated in Figs. 5 to 8 inclusive, and now being described, the auxiliary tube 25^a in the normal or inoperative position of the parts extends adjacent to and preferably parallel with the tubes 10^a and 11^a as shown in Fig. 6. In this condition the channel 28^a extends in a direction away from the channel 18^a which is accordingly sealed by the surface of the tapered portion 21^a and communication between the tubes 10^a and 20^a consequently cut off as shown best in Fig. 8. At the same time the plug 34 is preferably in a position with the passage 34^b out of registry with the channels 19^a and 30^a so that these channels are disconnected and the channel 19^a and consequently the tube 11^a is securely sealed by the surface of said plug also as shown best in Fig. 8. When it is desired to use the instrument, it may first be connected with the source of pressure to be measured after which the plug 34 may be rotated in the cap 15^a by means of the handle 34^a until the passage 34^b registers with the channels 19^a and 30^a which are thus brought into communication with each other and connect the tube 11^a with the source of pressure or other force to be measured. If the tube 25^a is now moved to the position shown in Fig. 5 the instrument will be ready for use, this movement of the said tube 25^a having rotated the tapered portion 21^a of the plug 20^a in the cap 14^a so as to bring the end of the channel 28^a into registry with the channel 18^a and the tubes 10^a and 25^a into communication with each other. It is, of course, to be understood that the tube 25^a may be first moved as described and the instrument then connected with a source of pressure or other force and the plug 34 then manipulated to connect the channels 19^a and 30^a if this procedure is preferred. In either case the operation and function of the instrument is the same as the one shown in Figs. 1 to 4 inclusive. The last form of my invention thus has substantially the same advantages of the form of my improvement first described, as will be clearly apparent from the illustration and description. In both forms after the instrument has been used, the tubes 25 or 25^a is returned to the position shown in Figs. 2 and 6 respectively in which position in Fig. 2 both the tubes 10 and 11 are securely and automatically sealed while in Fig. 6 the tube 10^a is automatically sealed and the tube 11^a closed by operating the plug 34 to disconnect the channels 19^a and 30^a. It is also to be understood that suitable stops may be provided if desired to limit the rotative movements of the tubes 25 and 25^a and the plug 34 in such a manner as to bring the various channels into and out of communication with each other. In addition to this, it will readily be seen that in the form of my improvement shown in Figs. 5 to 8 inclusive the tube 25^a may be mounted on the tube 10^a in the opposite way from that shown so as to move in a plane extending between the tubes 10^a and 11^a instead of being movable in a plane located outside of said tubes as in the illustration. In other words if constructed in this manner the tube 25^a in the folded or inoperative condition of the instrument would occupy a position similar to that of the tube 25 in Fig. 2 and in the unfolded or extended condition, said tube 25^a would be positioned as is the tube 25 in Fig. 1. The plugs 20 and 20^a with their passages or channels constitute valves which are opened or closed as the tubes 25 or 25^a are actuated and either establish or disestablish communication between the tubes 10 and 25 and 10^a and 25^a according to the positions of said tubes 25 and 25^a. It will be further understood that as the indicating medium 13 or 13^a is moved upward in the tubes 25 or 25^a the air above the same in said tubes will either be forced out of the open ends thereof or through the air vents 26 or 26^a.

Various changes in the specific forms shown and described may be made within the scope of the claims without departing from the spirit of my invention.

I claim:

1. A manometer comprising a main tube, an auxiliary tube movably mounted on said main tube and movable to an operative position to form a continuation of said main

- tube in a lengthwise direction, a coupling member communicating with said main tube and adapted to connect the manometer with the source of the force to be measured and 5 provided with means for establishing and disestablishing communication between said main tube and said coupling member, means for establishing and disestablishing communication between said main and auxiliary 10 tubes and an indicating medium normally in said main tube and movable into said auxiliary tube when the latter is in its operative position.
2. A manometer comprising a main tube, 15 an auxiliary tube movably mounted on said main tube and movable to an operative position to form a continuation of said main tube in a lengthwise direction, a coupling member adapted to connect the manometer 20 with the source of the force to be measured, means movable with said auxiliary tube adapted to concurrently establish and disestablish communication between said main and auxiliary tubes and between said main 25 tube and said coupling member as the auxiliary tube is moved to and from an operative position and an indicating medium normally in said main tube and movable into said auxiliary tube when the latter is in its 30 operative position.
3. A manometer comprising main tubes communicating with each other, a rotatable member mounted thereon and provided with a nozzle, an auxiliary tube carried by said 35 rotatable member and normally extending between said main tubes in an inoperative position and movable to an operative position to form a continuation of said main tubes in a lengthwise direction, said rotatable member being provided with channels 40 whereby communication between said auxiliary tube and said main tubes and between said main tubes and said nozzle is concurrently established and disestablished as the auxiliary tube is moved, and an indicating medium normally in said main tubes and movable into said auxiliary tube when in its 45 operative position.
4. A manometer comprising main tubes 50 communicating with each other, caps secured on the free ends of said tubes each provided with a channel communicating with a main tube and alining transverse bores, a rotatable member journaled in said 55 bores, an auxiliary tube carried by said rotatable member and normally extending between said main tubes in an inoperative position and movable to an operative position to form a continuation of said main tubes 60 in a lengthwise direction, said rotatable member being provided with disconnected passages one of which forms an inlet passage and the other of which communicates with said auxiliary tube, both passages being arranged to be brought into and out of 65

registry with said channels as the auxiliary tube is moved to and from an operative position whereby communication between the main tubes and the auxiliary tube and the inlet passage is concurrently established and 70 disestablished and an indicating medium normally in said main tubes and movable into said auxiliary tube when in its operative position.

5. A manometer comprising two main 75 tubes in communication with each other, an auxiliary tube pivoted on one of said tubes and normally extending parallel thereto in an inoperative position, said auxiliary tube being movable to an operative position to 80 form a continuation of said main tube in a lengthwise direction, a valve connected with said auxiliary tube and adapted to establish and disestablish communication between said main and auxiliary tubes as the auxiliary tube is in an operative or an inoperative position, a nozzle for the other main tube, means arranged to connect or disconnect said nozzle from said main tube and an indicating medium normally in said main 85 tubes and movable into said auxiliary tube when in its operative position.

6. A manometer comprising two main 90 tubes in communication with each other, an auxiliary tube movably mounted on said 95 main tubes and movable to a position to form a continuation thereof in a lengthwise direction, means for establishing communication between said main tubes and said auxiliary tube in its operative position, an 100 indicating medium arranged to be lowered in one of said main tubes and raised in the other and into said auxiliary tube, a portion of a scale on the main tube in which the indicating medium is lowered and co-operating with said indicating medium as the same descends in said tube, and a continuation of said scale on said auxiliary tube arranged to co-operate with said indicating medium as the same rises in the 110 other tube.

7. A manometer comprising a main section, means for connecting said manometer with a source of pressure, a tube section, arranged to form a continuation of said 115 main section in the direction in which the liquid rises when pressure is applied thereto from said source of pressure, and means comprising a valve whereby said tube section is hinged to said main section and communication between said sections is controlled so that said communication shall be either open or closed, one of said sections having a translucent face whereby the variations in the movement of the liquid column 120 may be measured.

8. The combination of a receptacle for a pressure-receiving end of a liquid column, a tube section having a bend connected with said receptacle, a second tube section, and 130

means comprising a valve whereby said second tube section is hinged to said first named tube section and communication between said sections is controlled, so that said communication shall be either open or closed, 5 graduations being provided whereby the height of a liquid column in said tube sections may be read.

9. In a manometer, the combination of an 10 upright receptacle for the pressure-receiving end of a liquid column, a tube section having a bend connected with said receptacle, a second tube section, and means comprising a

valve whereby said second tube section is hinged to said tube section first named, and 15 communication between said sections is controlled, graduations being provided whereby the height of a liquid column in said manometer may be read.

In testimony whereof I have hereunto set 20 my hand in the presence of two subscribing witnesses.

RALPH F. SCHNEIDER.
